UNITED STATES PATENT OFFICE.

RUSSEL B. OWEN AND OLNEY B. FULLER, OF DETROIT, MICHIGAN, ASSIGNEES TO THE SMITH & OWEN HEATER COMPANY, OF SAME PLACE.

CIRCULATING HOT-WATER HEATER.

SPECIFICATION forming part of Letters Patent No. 363,165, dated May 17, 1887.

Application filed May 10, 1886. Serial No. 201,672. (No model.)

To all whom it may concern:

Be it known that we, RUSSEL B. OWEN and OLNEY B. FULLER, of Detroit, in the county of Wayne and State of Michigan, having invented new and useful Improvements in Circulating Hot-Water Heaters; and we do hereby declare that the following is a full, clear, and exact description thereof, reference being had to the accompanying drawing which forms a part of this specification.

This invention relates to certain new and useful improvements in circulating hot-water heaters; and it consists in the peculiar combinations and the novel construction and arrangement of parts, all as more fully hereinafter described and claimed.

In the accompanying drawing our invention is shown in sectional elevation, and A represents a boiler consisting of a double shell surrounding and inclosing an annular water-space, a.

F is a vertical or direct pipe, communicating with the water space of the boiler near its top and leading to a coil or radiator, G, whence it 25 descends, following the pipe H, which leads into the water-space of the boiler near its lower end.

C is a feed-pipe, forming a communication between an elevated tank, D, and the lower part of the water-space of the boiler, preferably, although not necessarily, through a T at the lower end of the return-pipe, as shown at b.

E is an overflow-pipe from the tank.

I is a water-supply pipe discharging into said tank, and provided with a valve, c, which is operated by means of the float J, secured at the end of the arm d, the other end of which is connected with the valve.

In practice, the boiler, circulating pipes, and feed-pipe being filled with cold water, and the tank filled to the top of the overflow-pipe, a fire is made in the furnace. As water under certain conditions of heat expands, such expansion will force a small portion of the water in the feed-pipe to discharge into the tank and out of the same through its overflow-pipe. If a small quantity of hot water is now wanted

for any purpose, it may be obtained by opening the cock K in the return-pipe H. What is withdrawn will be immediately supplied from the tank through the feed-pipe, the weight of the column of water in such pipe being sufficient to overcome the pressure in the boiler. This lowers the surface of the water in the tank below the top of the overflow, and the float, following the falling surface, opens the valve in the supply-pipe and lets the water therefrom fill the tank again to the proper height. If from any cause a leak or obstruction should be found in the circulating-pipes, the water may be withdrawn from such pipes by closing the valve e in the vertical pipe F and the valve h in the return-pipe H and opening the cock K in the latter-named pipe, thereby avoiding the necessity of drawing off the water in the boiler, as has heretofore been required.

Some of the features herein shown, but not claimed, are shown and claimed in an application filed of even date herewith by Peter Smith and Olney B. Fuller, and numbered 201,670.

What we claim as our invention is—

The apparatus described, consisting of the boiler A, having water-space a, a tank connected with said water-space near the top thereof, direct pipes F, communicating with said tank, independent coils G, return-pipe H, connected with the bottom of the water-space, elevated tank D, feed pipe C, connecting said tank with the lower part of the water-space, the return-pipe H', connected at b with the feed-pipe C, overflow-pipe E, feed-pipe I to said tank, valve c in said feed-pipe, float J, regulating said valve, the cock e in the direct pipe F, valve h in the return-pipe, and the cock K in the return-pipe between the valves e and h, all combined, arranged, and operating substantially as and for the purposes specified.

RUSSEL B. OWEN.
OLNEY B. FULLER.
